(57) **CLAIM**

I claim the ornamental design for an elastomeric block for multi-modal play, as shown and described.

DESCRIPTION

FIG. 1 is a top, front, right perspective view showing the elastomeric block for multi-modal play on its bottom side, which is a mirror image of the bottom, back, left perspective view.

FIG. 2 is a back, bottom, left perspective view of the elastomeric block for multi-modal play on its front side, which is a mirror image of the front, top, right perspective view.

FIG. 3 is a cross section view taken in the direction of 3-3 in FIG. 1; and,

FIG. 4 is a perspective cross section view taken in the direction of 4-4 in FIG. 2.

The shading lines shown in the drawings represent the approximate three-dimensional contour of the design, and are not intended to indicate surface decoration.
